(57) **CLAIM**

We claim the ornamental design for an interchangeable shoe heel, as shown and described.

DESCRIPTION

FIG. 1 is a top, right perspective view of an interchangeable shoe heel showing the new design;

FIG. 2 is a bottom, front perspective view thereof;
FIG. 3 is a bottom, left perspective view thereof;
FIG. 4 is an exploded, top, right perspective view thereof;
FIG. 5 is an exploded, bottom, left perspective view thereof;
FIG. 6 is a front, elevation view thereof;
FIG. 7 is a rear, elevation view thereof;
FIG. 8 is a right, elevation view thereof;
FIG. 9 is a left, elevation view thereof;
FIG. 10 is a top view thereof;
FIG. 11 is a bottom view thereof;
FIG. 12 is a top, right perspective view of the upper portion thereof;
FIG. 13 is a bottom, rear perspective view of the upper portion thereof;
FIG. 14 is a front, elevation view of the upper portion thereof;
FIG. 15 is a rear, elevation view of the upper portion thereof;
FIG. 16 is a right, elevation view of the upper portion thereof;
FIG. 17 is a left, elevation view of the upper portion thereof;
FIG. 18 is a top, elevation view of the upper portion thereof;
FIG. 19 is a bottom, elevation view of the upper portion thereof;
FIG. 20 is a top, right perspective view of the lower portion thereof;
FIG. 21 is a front, elevation view of the lower portion thereof;
FIG. 22 is a rear, elevation view of the lower portion thereof;
FIG. 23 is a right, elevation view of the lower portion thereof;
FIG. 24 is a left, elevation view of the lower portion thereof;
FIG. 25 is a top, elevation view of the lower portion thereof;
FIG. 26 is a bottom, elevation view of the lower portion thereof;
FIG. 27 is a top, right perspective of the lower portion thereof;
FIG. 28 is a front, elevation view of the lower portion thereof;
FIG. 29 is a rear, elevation view of the lower portion thereof;
FIG. 30 is a right, elevation view of the lower portion thereof;
FIG. 31 is a left, elevation view of the lower portion thereof;
FIG. 32 is a top, elevation view of the lower portion thereof; and,
FIG. 33 is a bottom, elevation view of the lower portion thereof.
